UNITED STATES PATENT OFFICE

2,447,866

SHIFTER ARRANGEMENT

Edward O. Merline, Detroit, Mich., assignor to
Norman L. Boxwell, Detroit, Mich.

Application September 28, 1945, Serial No. 619,223

8 Claims. (Cl. 192—.02)

1

This invention relates to improvements in shifter arrangements, and refers particularly to a shifter arrangement for attachment to a motor, primarily an electric motor, for operating a clutch on the motor shaft.

It is an object of the invention to provide a shifter arrangement including a baseplate having bearings thereon for supporting a shifter rod for axial movement, means for mounting the baseplate upon a motor, and a rod supported on the baseplate for axial movement in parallelism with the motor shaft so that a clutch upon the latter is moved into engaged or released position by a conventional shifter yoke carried by and projecting from the rod upon movement of the latter.

Another object of the invention is to provide a shifter arrangement having adjustable mounting means thereon so that the latter may be moved to the required positions for attachment to the conventional fastening means by which the end plates are secured to a motor frame. In this way I aim to provide a mechanism which may be mounted upon motors the fastening means for the end plates of which are differently spaced both transversely and longitudinally of the motor shaft.

A further object of the invention is to provide such a shifter arrangement which is cheap and simple to manufacture and assemble, efficient in operation, and which is so constructed that only a few different sizes need be manufactured to cover a relatively wide range of motor sizes.

Having thus stated some of the objects and advantages of the invention I will now describe it in detail with the aid of the accompanying drawings, in which:

Figure 1 is a perspective view of one embodiment of my shifter arrangement mounted on an electric motor.

Figure 2 is a plan view thereof.

Figure 3 is an end view, and

Figure 4 is a side elevation.

Figure 5 is a detail showing a slightly modified form wherein axial movement of the rod is obtained by electrical means.

Figure 6 is a perspective view showing a somewhat modified form of my shifter arrangement.

Figure 7 is a plan view of Figure 6, and

Figure 8 is an end view thereof.

I will first describe one of the many forms of clutch arrangements to which my invention may be advantageously applied. Referring to the drawings, 1 designates an electric motor having end plates 2 through which bolts 3 extend out-

2

wardly and have nuts 4 on their outer extremities to hold the said plates in position. The motor shaft 5 has a clutch plate 6 thereon, and coaxial with the shaft 5 a second shaft 7 is suitably supported and has a clutch plate 8 mounted for axial movement thereon to coact with the plate 6. Axially movable on the shaft 7 with the plate 8 is a collar 9 having a conventional yoke 10 in engagement therewith by movement of which in a direction parallel with the axes of the shafts 5 and 7 the clutch plate 8 is engaged with or released from the clutch plate 6.

11 designates a baseplate having longitudinally aligned bearings 12 thereon which support a rod 13 for axial movement, and mounted on the said rod for movement therewith is a yoke 10. Suitable means are provided for supporting the baseplate 11 upon motors of various sizes so that the rod 13 is maintained parallel with the motor shaft 5.

In the arrangement shown in Figures 1 to 4 inclusive, openings 14, which may consist of elongated slots extending parallel with the rods 13 are formed through opposite sides of the baseplate 11. 15 denotes bearings having laterally projecting elements 16 thereon threaded at their outer extremities 17 one of which projects through each of the slots 14 and has a nut 18 on its outer end to hold its bearing 15 relative to the baseplate. Extending through each pair of bearings 15 parallel with the rod 13 is a shaft 19. On each shaft, usually outwardly of the bearings 15, two members 20 are pivotally mounted. Formed through each member is an aperture 21 for the passage of one of the bolts 3. Thus by tightening the nuts 4 the members are securely held in position and the baseplate 11 rigidly supported.

As the members 20 are pivoted on the shafts 19 their apertures 21 may be variously spaced transversely of the motor 1 to suit the transverse spacing of the bolts 3. Again as the members are also axially movable on the shafts 19 their spacing along the latter is subject to material adjustment. Consequently a shifter unit of any given size may be satisfactorily applied to motors of different sizes.

In Figures 6-8 inclusive, the base plate 11 is provided with apertures 14a in the form of elongated slots extending from opposite ends of the baseplate 11 and in axial alignment with the bearings 12. Projecting through each aperture 14a is an element 16a threaded at its extremity 17a to receive a nut 18a by which the said element is secured to the baseplate. Formed on the

opposite ends of the elements are members 20a each having an aperture 21a therethrough for the passage of one of the bolts 3 therethrough. In the construction herein shown the element 16a and the member 20a consist of an eyebolt so that when the nuts 18a are tightened the underside of the baseplate is drawn down upon the frame of the motor 1.

To move the yoke 10 the rod 13 may be moved axially in any preferred manner. The arrangement shown in Figures 1 to 4 includes a slot 22 formed through the rod 13 intermediately of its length through which a lever 23 extends which is pivotally supported on a pin 24 projecting from the baseplate 11. In Figures 6 to 8 axial movement is imparted to the rod 13 by a lever 23a pivoted at 24a on the baseplate 11. In that case however a pin 35 extends from the rod 13 and engages a slot in the lever 23a so that movement of the latter also moves the rod axially. If desired electrical means may be used for moving the rod 13 axially such as a solenoid 25 illustrated in the modification shown in Figure 5.

While in the foregoing the preferred embodiments of the invention have been described and shown it is understood that the constructions herein shown are susceptible to such further alterations and modifications as fall within the scope of the appended claims.

What I claim is:

1. A shifter arrangement including a baseplate having aligned bearings thereon, a rod supported for axial movement in the bearings, means for moving the rod axially, members carried by the baseplate for attachment to opposite ends of a motor for supporting the baseplate and holding the rod parallel with the motor shaft, and a yoke fixed on the rod.

2. A shifter arrangement including a slotted baseplate having aligned bearings thereon, a rod supported for axial movement in the bearings, means for moving the rod, elements projecting through the slots and secured at one extremity to the baseplate, members carried by the elements at their opposite extremities, means for securing the members to opposite ends of a motor and supporting the baseplate with the rod in parallelism with the motor shaft, and a yoke fixed on the rod.

3. A shifter arrangement including a baseplate having aligned bearings thereon, a rod axially movable in the bearings, means for moving the rod, a motor including a motor shaft, means carried by the baseplate for attachment to opposite ends of a motor, a second shaft in alignment with the motor shaft, a clutch mechanism for engaging and disengaging the two shafts, and a yoke fixed on the rod in engagement with the clutch mechanism.

4. In an arrangement of the character described, the combination with a motor having a

shaft projecting from one end and fastening means extending from opposite ends, a second shaft supported in alignment with the motor shaft, and a clutch mechanism for engaging the two shafts, a base plate, means carried by the baseplate for engaging the fastening means and supporting the plate, aligned bearings on the baseplate parallel with the motor shaft, a rod mounted for axial movement in said bearings, means for moving the rod, and a yoke fixed on the rod in engagement with the clutch mechanism.

5. The combination set forth in claim 1, wherein the members are supported for pivotal movement relative to the elements.

6. The combination set forth in claim 1, wherein the members are mounted for movement relative to the baseplate.

7. In an arrangement of the character described, the combination with a motor having fastening means projecting from opposite ends and a shaft extending from one of said ends, a second shaft mounted in alignment with the motor shaft, coating coupling means on the two shafts, the coupling means on one of the shafts being axially slidale and including a yoke engaging member, of a baseplate, aligned bearings on the baseplate parallel with the motor shaft, a rod mounted for axial movement in the bearings, means for moving the rod axially, a yoke fixed on the rod in engagement with the yoke engaging member, elements supported by the baseplate, shafts dependingly carried by the elements, and members mounted on the dependingly carried shafts engaged by the fastening means whereby the baseplate is supported by the motor.

8. A shifter arrangement including a baseplate slotted from opposite extremities and having bearings thereon in alignment with the slots, a rod mounted for axial movement in the bearings, means for moving the rod axially, elements extending through the slots, means securing one extremity of each element on the baseplate, members integral with the opposite extremities of the elements for attachment to the fastening means projecting from opposite ends of a motor, and a yoke on said rod for movement therewith for operating a clutch mechanism mounted at least in part on a shaft projecting from the motor.

EDWARD O. MERLINE.
